UNITED STATES PATENT OFFICE.

SAMUEL JOHNSTONE, OF SPARKS, NEVADA, ASSIGNOR OF ONE-THIRD TO F. H. SEAVEY, OF RENO, NEVADA, AND ONE-THIRD TO FRED W. STEINER, OF SPARKS, NEVADA.

BATHTUB MAT.

Application filed June 17, 1926. Serial No. 116,676.

This invention relates to a covering mat for the outer rim of a bath tub, which aims as its principal object to afford means by which the bather may obtain a non-slip 5 chase to lift himself to an erect position when getting out of the tub.

More specifically, the invention comprehends a mat of the character described which is so formed and constructed as to render the 10 same self-retaining on the edge of the tub for preventing accidental displacement.

The invention furthermore comprehends a mat for covering the outer edge of a bath tub, which in addition to affording a safe 15 and convenient means for leaving the tub, also functions as a non-slip rim for hanging a bath mat thereon or as a seat for the bather on the edge of the tub.

The invention furthermore aims to provide a device of the character set forth which is comparatively simple in its construction, 20 inexpensive to manufacture, and which is highly efficient in its purpose.

With the above recited and other objects in 25 view, reference is had to the following specification and accompanying drawings, in which there is exhibited certain examples or embodiments of the invention which are in no way intended as limitations upon the 30 scope of the appended claims as it is to be clearly understood that variations and modifications which properly fall within the scope of said claims may be resorted to when found expedient.

35 In the drawings—

Figure 1 is a perspective view illustrating the mat in applied position on the edge of a bath tub;

Fig. 2 is a sectional view therethrough;

40 Fig. 3 is a plan view of the mat in flattened out condition prior to the formation and vulcanizing of the same in its final form;

Fig. 4 is a sectional view therethrough 45 taken approximately on the line 4—4 of Fig. 3, and

Fig. 5 is a sectional view of a modified form.

Referring to the drawings by characters of 50 reference, the mat includes a substantially rectangular body or strip 10 of rubber, which is provided with an embedded fabric reinforcing layer 11 of cotton or any other suitable fabric which reinforcing layer is

formed with a plurality of rows of cutaway 55 regular portions 12 at which point the body is solid between the surfaces and which solid portions are provided with apertures 13. In the final formation the rubber is vulcanized so that the strip or body 10 is of a cross- 60 sectional formation approximating the cross-sectional configuration of the upper and outer edge A of the tube B, but of slightly less size so that when engaged thereover it will snugly fit and grip the edge to retain 65 itself in place against accidental displacement.

In use it is not intended that the bather shall grasp the mat but shall simply place his hand on the upper surface to afford a 70 non-slip portion with which the hand engages to assist the bather in arising or leaving the tub. The apertures 13 will present a slightly roughened or non-slip surface in 75 addition to this characteristic which is inherent in rubber.

The mat will also serve as a seat for the upper outer edge of the tub upon which the bather may rest, or with which the feet may be engaged, in addition to serving as a non- 80 slip supporting surface for the bat mat.

In the modified form of the invention, the strip is provided with an inwardly projecting bead 14 which presents a comparatively wide flat upper surface 15, while in other 85 respects the construction is identical with that described in the preferred embodiment.

What is claimed is:

1. As a new article of manufacture, a mat for the upper and outer edge of the bath tub, 90 comprising a contractile, elongated, rectangular body of a cross-sectional configuration approximating the cross-sectional shape of the edge of the tub and of slightly less size than said edge, said body having a fabric 95 reinforcing layer embedded therein, said reinforcing means having rows of elongated cutaway portions.

2. As a new article of manufacture, a mat for the upper and outer edge of bath tubs, 100 comprising a contractile, elongated, rectangular body of a cross-sectional configuration approximating the cross-sectional shape of the edge of the tub and of slightly less size than said edge, said body having a fabric 105 reinforcing layer embedded therein, said reinforcing means having rows of elongated cut-away portions formed with apertures

through the solid portions of the body extending through the cut-away portions.

3. As a new article of manufacture, a mat for the upper and outer edge of bath tubs, comprising a contractile, elongated, rectangular body of a cross-sectional configuration approximating the cross-sectional shape of the edge of the tub and of slightly less size than said edge, said body having a fabric re-

inforcing layer embedded therein, said reinforcing means having rows of elongated cut-away portions formed with apertures through the solid portions of the body extending through the cut-away portions, and an inwardly projecting bead on said body 15 presenting a relatively wide flat upper surface.

SAMUEL JOHNSTONE.
